UNITED STATES PATENT OFFICE.

HENRY G. SMITH, OF HUTCHINSON, KANSAS.

DESIGN FOR DESK FURNITURE.

SPECIFICATION forming part of Design No. 17,352, dated May 17, 1887.

Application filed April 14, 1887. Serial No. 234,842. Term of patent 7 years.

To all whom it may concern:

Be it known that I, HENRY G. SMITH, residing at Hutchinson, in the county of Reno and State of Kansas, have invented and produced 5 a new and original Design for an Article of Furniture for Desks, of which the following is a specification, reference being had to the accompanying drawing, forming part thereof, in which drawing I have illustrated my newly-10 designed article of furniture for desks by a perspective view.

A refers to the base, which is provided with inclined sides *a*, each of which is provided with openings, in which slide drawers *A'*, said 15 drawers being provided centrally with suitable knobs. The base *A* is provided with a flat top, and at each corner are located depressions *B*. Adjacent to the depressions *B*, in which may be placed ink-wells, there are 20 pen-racks *B'*.

From the center of the base *A* extends a cylindrical standard, *C*, the upper end of which is provided with a suitable ornament, and upon this standard are secured frames *D* and 25 *D'*, the lower frame, *D*, being of a larger size than the one located immediately above.

The leading feature of my design consists in the shape and configuration of the base and cases, said cases being supported centrally above the base.

An article of furniture constructed as shown in the accompanying drawing, aside from its utility, presents to the eye a pleasing effect, and the design, when placed upon a desk, will tend to make it attractive and will give an ornamental appearance to the same.

I claim—

The design for desk furniture herein shown and described, the same consisting of a base having inclined edges and a flat top with depressions at the corners and pen-racks thereon, a circular central standard supporting frames *D* and *D'*, of different sizes, said standard terminating in an ornamental top.

In testimony whereof I affix my signature in presence of two witnesses.

HENRY G. SMITH.
